ELECTRIC AND AUTOMATIC FUEL VAPOR-
IZER

Alois Skok and Noble O. Binley, Pasadena, Calif.

Application December 9, 1937, Serial No. 178,966

6 Claims. (Cl. 123—122)

Our invention relates to electrically energized and automatically operated vaporizers, adapted for fuels used in the internal combustion engines, said fuels belonging to the hydrocarbon class and/or their derivatives, which are of high or low flash point and involatile liquid or gaseous form.

Therefore, an object of our invention is to provide an element, which is placed within the intake passage of the internal combustion engine, said element being adapted to receive and maintain a temperature supplied by the electrical energy while it passes therethrough, thus causing said element to be heated at the temperature required and consequently causing the disintegration of the fuel into a gaseous form.

Manifestly, an object of our invention is to provide a vaporizer which is electrically heated and which will cause the passing gases to become disintegrated into fine gaseous atoms, and therefore, causing quick ignition of the gaseous charge in the cylinders of the engine and consequently preventing the formation of the carbon therein.

25 Further object of our invention is to provide said vaporizer with means for controlling the air passage into the intake manifold of the internal combustion engine, so that an additional volume of air may be intermixed with the heated gases and thus increasing the volatility of the gas mixture.

Another object of our invention is to provide a magnetically energized contact point which will cause the electric current to flow through the heating element, so that the fuel vaporizer may be effected and so maintain during the operation of the engine.

Further object of our invention is to provide a suitable vacuum cylinder which is connected to the intake manifold of the internal combustion engine, and which is provided with a suitable contact means for allowing the electric current to pass therethrough and to the heating element of the apparatus during the operation of the engine.

45 Another object of our invention is to provide said heating element with a suitable mounting adaptor, which is for holding said element in central position and in the path of the passing atomized fuels, coming from the carburetor, and which is so arranged whereby the maximum heat may be maintained at the point or a place where the gases must invariably pass through and, therefore, breaking up the gas molecules in readiness for the combustion.

Further objects and advantages of our invention as will hereinafter more fully appear, we attain by the construction herein shown on the drawing and described in the specification forming a part of our application.

Reference is had to the accompanying drawing, in which the similar reference characters denote the similar parts.

In the drawing:

Fig. 1 shows the partly elevational and partly cross-sectional view of the heating and controlling apparatus, taken on the line 1—1 of the Fig. 2.

Fig. 2 shows the top view, partially cross-sectional, showing the heating elements and their connections, taken on the line 2—2 of the Fig. 1.

Fig. 3 shows the cross-sectional view of the insulators taken on the line 3—3 of the Fig. 1.

Fig. 4 shows the top elevational view of the air valve taken in the direction of the arrow 4.

Fig. 5 shows the apparatus connected to the instrument board, having its connection extended in modified form.

Describing our invention more in detail, said invention comprises an element 2, the vacuum controlled switch 4, which is also provided with an air valve member 6, and which inter-connects the vacuum cylinder 8, including the intake manifold 10, also having a supplemental air valve 12, provided with an air inlet needle control 14.

30 Said element 2 comprises a pair of conically spiral coils 16 and 18 respectively, which are made of suitable electrical heat resisting material, and which, has the small ends 20 and 22 respectively connected to the bushings 24, one 35 on each end thereof, said bushing being mounted upon a stud member 26 and supported in place by means of suitable nuts 28, so that the radial space 30 between said coils 16 and 18 is approximately $\frac{1}{8}$ th of an inch.

40 In order to hold said stud member 26 in proper position, and within said manifold 10, the stud end 32 is attached to a cross bar member 34, and held in place by means of lock nuts 36, so 45 that a relatively central position of the said element 2 within the manifold 10 may be had.

Said cross bar member 34 is placed within a recess 38 of the adaptor 40, which is made of insulating material having its contact end 42 extended as shown, also having a suitable insulating washer 44 interposing between the said adaptor 40 and the manifold flange 46, and, in order to insure the contact for the element coils 16 and 18, suitable lead ends 48 and 50 are connected 55

to the copper washer 52, as shown in Figs. 1 and 3.

Said adaptor 40 is provided with suitable holes 54 which correspond to the size and the position 5 of the bolts used in bolting the carburetor flange 56 to the said manifold flange 46, and, said adaptor 40 is also provided with suitable passages 58 and 60, which are threaded as shown and adapted to hold in place the said air valve member 6 and the supplemental air valve 12.

The air valve member 6 comprises a body 62 which is provided with a chamber 64 wherein a suitable valve seat 66 is placed and which is adapted to receive an air passage central member 15 68 of which, one end is pointed as at 70 in conformity to the said valve seat 66, while the other end is threaded, as shown, for inter-engaging the said body 62 and to provide the necessary adjustment for the volume of air which may pass 20 through, and which, may be locked in place, in adjusted position, by means of the locking nut 72.

Said body member 62 is provided with a side outlet passage 74 having a threaded socket 76 which is to receive the threaded inlet section 78 of 25 the said cylinder 8; said cylinder 8 comprising a cap member 80 which is provided with a suitable neck member 82 and to which the insulating bar member 84 is attached, and, the said neck member 82, through its passage, is provided with a 30 guiding collar 86 for the purpose to hold the stem member 88 in place.

The end 90 of the said stem 88, within said cylinder 8, is provided with a washer 92 and also having a retaining cup member 94 associated 35 therewith, which is held in place by means of a lock washer 96 and the nut 98, as shown, while the other end 100 is provided with a pair of lock nuts 102 which are connecting the transverse bar member 104, having a hole 106 provided therein to 40 insure free movement of the stem end 100 when the apparatus is in operation. In order to hold the transverse bar member 104 and the cup member 94 in a relatively upper position, in order to break the points of contact 108, said stem member 45 98 is provided with a suitable spring member 110, which is held in place by means of a washer 112 and locked in place by means of a pin 114.

The said switch 4, comprises an insulating bushing 116 which is held in engaged position to 50 the said insulating bar 84 by means of the shank member 118, also, it is provided with a locking nut 122, while the extended end is provided with the contact element 124, thus forming the contact point 108.

55 Said transverse bar member 104 is provided with a suitable insulating strip 126 having a resilient member 128 attached thereto by means of a rivet 130; said resilient member 128 comprises a loop end 132 which is provided with the contact 60 element 134, while the other end extends parallelly to the end of the said transverse bar 104, being held therein by means of the contact rivet 136, then, said resilient member forming a U-turn as at 138 in order to provide a springing effect for 65 the said bar member 104, and, in order to hold it in its relative position, a suitable bracket 140 is provided therein, which is held upon said insulating bar 84 by means of suitable screws 142 and to which the end 144 of the said resilient member 70 128, is attached, as shown.

The said transverse bar member 104 is also provided with a magnetic contact plate 146, which is positioned in a close proximity to the core 148 of the magnet member 150, which is positioned 75 upon the end 152 of the said insulating bar 84, so

that, the suction produced by the pistons within the engine cylinders will cause the cup member 94 to move downwardly, closing the contact point 108, or, by energizing the magnet member 150, the magnetic influence will cause the core member 148 to attract the contact plate 146, and closing the said contact points 108, the purpose and the operation of which will be presently described. 5
ment 2, a suitable electric current source may be

In order to provide heat energy to the said ele- 10
used, such as a storage battery 154, which is provided with lead wires 156, connecting the contact rivet 136, also, having a lead wire 158 connecting the switch 160, and which connects the lead wire 162 of the magnet member 150: said magnet 15 member having a lead wire 164 connecting the manifold ground wire 166, which is grounded as at "G". When the contact points 108 are closed, by the action of the suction influencing the piston cup 94 of the cylinder 8, or, by closing the switch 20 160, the current passes through the lead wires 156 to the resilient member 128, passing through the contact element 134 to the contact element 124, which leads into the contact rod 120 and to which a lead wire 168 is attached, thus passing the cur- 25
rent to the wire end 170, which is connected to the contact end 42 of the cross bar member as at 172, and thus allowing the current to pass through the stud 26, which causes the current to heat the element ends 20 and 22, and then passing through 30 the lead ends 48 and 50 to the contact plate 52, and finally to the ground wire 166 in completing its circuit.

When the engine is functioning the elements 2 will be heated as soon as the suction, created by 35 the action of the piston in the cylinders, will cause the cup 94 to be drawn downwardly, causing the contact points 108 to close, or, when deemed advisable, the switch 160 may be closed, causing the magnetic influence in the magnet 150 to energize the core 148, which by attracting the contact plate 146 will close the contact points 108, then the passing current flowing from the battery 154 will heat the elements, so that, when the atomized fuel vapor passes therethrough the heat will cause 45 the vapor to vaporize said fuel, and will break down the atomic structure of the passing vapor, causing said vapors to become highly volatile and thus insuring perfect combustion.

It may be noted that in order to insure the 50 volatility of the gases, it is invariably necessary to supplant an additional volume of air, therefore, the said supplemental valve 12, connected to said adaptor 40, is provided with a valve seat 174, which is positioned within the valve body 176, 55 and wherein a plurality of passages 178 are positioned, so that, by increasing the opening between the valve seat 174 and the port 180 of the needle valve 14, more air may pass therethrough and into the chamber 182, further, because of the position of the air inlet 60 in respect to the inter-periphery of the said manifold opening or chamber, the rushing air will cause said mixed gases to whirl and therefore insuring the mixing of the gases with the new coming air. 60
65

Further, it may be noted, that in order to prevent possible spark from the contact points 108, which may become a cause for igniting gases, a suitable cover 184 is provided, enclosing said contact switch 4 of the said apparatus, and having 70 the valve member 6 provided with a suitable tubular extension 186, the end of which connects with the passage 58 at the adaptor member 40, as shown in Fig. 5.

While we have thus described our invention 75

with great particularity it will be clear that the same may be modified throughout a wide range.

We, accordingly, do not propose to be limited to the exact details of construction herein shown and described in the specification, but reserve the rights in practice to make necessary changes and modifications, which may come within the scope of the appended claims.

We claim as our invention:

1. In the apparatus of the class described, comprising, electrically heating means positioned in the manifold and the path of the passing gases, adapted for vaporizing the hydrocarbon fuel while passing through the intake manifold of the internal combustion engine, a magnetically influenced switch means connected to said apparatus and associated with said electrically heating means for automatically closing the electric current controlling switch, thus, causing, the electric current to pass through the said electrically heating means and for allowing pre-heating of the said heating means before and during the operation of the internal combustion engine.

2. In the apparatus of the class described, comprising, automatically controlled and electrically heated means positioned in the intake manifold and the path of the passing hydrocarbon gases, adapted for heating and disintegrating the hydrocarbon fuel, while passing through the said intake manifold of the internal combustion engine, a magnetically influenced switch means associated with the said last mentioned means for causing the electric current to pass through the said heating means, and, an air valve member associated with said apparatus having its inlet air passage positioned at the inter-periphery of the said manifold and in close proximity to the said electrically heated means for causing the incoming air to inter-mix with the passing gases and thereby increasing the volatility of the heated vapors.

3. In the apparatus of the class described, comprising, electrically heating element means positioned in the intake manifold and in the path of the passing hydrocarbon gaseous fuel which is used in the internal combustion engine, vacuum controlling means associated with said electrically heating means for automatically controlling the electric current passing to the said heating means, and valve means connected to said manifold at a close proximity to the said heating means for controlling the passage of air into the

said manifold and for causing whirling effect upon the mixed gases therein.

4. In the apparatus of the class described adapted for vaporizing the fuel passing through the manifold of the internal combustion engine, said apparatus having a source of electric current associated therewith, and comprising, an adaptor member positioned between the carburetor and the said manifold, an electrically heating element centrally positioned within said manifold and in the path of the passing fuel gases, a vacuum controlled means connected to said adaptor, and a contact means associated with and controlled by the said vacuum means for controlling the flow of the electric current through said contact means and to the said heating element.

5. In the apparatus of the class described adapted for vaporizing the fuel passing through the manifold of the internal combustion engine, comprising, an electric heat element positioned within the passage of said manifold and in the path of the passing fuel vapors, a vacuum valve controlling means connected to said heat element for controlling the electric current passing therethrough, and air valve means connected to said manifold for controlling the air flow into said manifold and for inter-mixing the vaporized fuel with an additional volume of air and therefore increasing the volatility of the combustive gaseous vapors.

6. In the apparatus of the class described, adapted for vaporizing the fuel passing through the manifold of the internal combustion engine, comprising, a source of electric current, a magnet member associated with said apparatus for controlling the passage of the said electric current, a contact switch member positioned in close proximity to said magnet member, an electric element positioned within said manifold and in the path of the passing gaseous fuel and connecting the said contact switch, and a magnet controlling switch inter-connecting said source of electrical current, so that, when said switch is closed the electrically energized magnet will cause the magnetic influence to close the said contact switch and allowing the electrical energy to flow through and heat the said element, for causing the passing gaseous fuel to become disintegrated.

ALOIS SKOK.

NOBLE O. BINLEY.
